UNITED STATES PATENT OFFICE.

LEO RUMBOSKI, OF NEW YORK, N. Y., ASSIGNOR, BY MESNE ASSIGNMENTS, OF ONE-HALF TO JAMES S. LONGHURST, JR., OF BROOKLYN, NEW YORK.

PUMP CONNECTION.

SPECIFICATION forming part of Letters Patent No. 712,461, dated October 28, 1902.

Application filed February 3, 1902. Serial No. 92,417. (No model.)

To all whom it may concern:

Be it known that I, LEO RUMBOSKI, a citizen of the United States, residing in New York, borough of Queens, and State of New York, have invented certain new and useful Improvements in Pump Connections, of which the following is a specification.

This invention relates to an improved pump connection between a foot or hand pump and the valve-nipple of a pneumatic tire, said connection being designed with a view of facilitating the pumping action of the hand or foot pump by opening the valve of the nipple in a positive manner by the action of the connection in place of opening said valve by the action of the air compressed in the pump, which is equivalent to a loss of power when expanding a tire; and for this purpose the invention consists of a pump connection which comprises a socket provided with interiorly-beveled side walls, a spring-cushioned plunger in said socket, a perforated screw-cap for closing the socket and guiding the stem of the plunger, and an exteriorly-threaded shank 25 on the cap for making connection with the valve-nipple on the tire; and the invention consists, further, in certain details of construction and combinations of parts, which will be fully described hereinafter and finally 30 pointed out in the claims.

In the accompanying drawings, Figure 1 is a side elevation of my improved pump connection, showing it in position for use with a pneumatic tire and a foot-pump. Fig. 2 is a 35 side elevation of the same, drawn on a larger scale and shown as connected with the valve-nipple of a tire. Figs. 3 and 4 are vertical central sections of the connection, showing it, respectively, in normal position and in position when acted on by the air compressed in the pump; and Fig. 5 is a horizontal section on line 5-5, Fig. 3.

Similar letters of reference indicate corresponding parts.

Referring to the drawings, A represents a 45 foot or other pump for charging pneumatic tires; B, a pneumatic tire that is attached to a rim C; D, the valve-nipple of the tire; D', the valve of the pneumatic tire, and E the 50 pump connection, the ribbed shank e of which is connected in any approved manner with

the elastic tube F, that leads to the cylinder of the pump A.

The pump connection E is composed of a cylindrical socket e, the interior wall of which is made cylindrical adjacent to its closed end, beveled or tapering at its middle portion, and interiorly screw-threaded adjacent to its open end. Into the interiorly-threaded end of the socket e is screwed a centrally-perforated cap f, which is provided with a perforated exteriorly-threaded nipple f', that is adapted to be screwed into the interiorly-threaded end of the valve-nipple D of the tire B. On the nipple f' of the screw-cap f is placed a gasket 65 f'', of leather or other suitable material, by which a tight connection between the screw-cap and valve-nipple is secured when the nipple of the former is screwed into the nipple of the valve D. At the interior of the socket 70 e is arranged a plunger g, which is loosely fitted into the upper cylindrical portion of the socket e. The plunger g is provided with a stem g', of triangular cross-section, that is guided in the bore of the nipple f' of the screw-cap f, said plunger being cushioned by a helical spring g'', which is interposed between the plunger and the inner face of the cap f, as shown clearly in Figs. 3 and 4. When 75 the socket e is screwed in the nipple of the valve D', the stem of the plunger is in line with the stem of the nipple-valve, so that as soon as the air is compressed by the action of the piston in the pump A the plunger is pushed downward against the tension of its 80 spring, so that its stem acts directly on the stem of the spring-cushioned valve d of the nipple D and forces the valve in inward direction, so that the air under pressure is supplied to the interior of the tire. The downward motion of the plunger g is produced by 85 the action of air compressed in the pump at each downstroke of the piston, whereby the plunger is moved into the tapering portion of the socket and its stem into the bore 90 of the nipple f' of the screw-cap, so that the air under pressure can freely pass through the valve D into the tire, as shown by the arrows in Fig. 4. With the upward stroke 95 of the pump-piston a suction is created and 100 the plunger returned into its normal position, so as to release thereby the stem d of the

valve of the tire, so that the valve is returned by its spring into normally closed position. The next downward motion of the pump-piston again supplies air through the socket and 5 valve into the tire until the same is expanded to its full extent. When the tire is expanded, the connection E is unscrewed from the nipple of the valve and the usual screw-cap applied to the same. Whenever the tire is to 10 be expanded again, the screw-cap of the valve-nipple is removed and the connection E screwed into the nipple D, as shown in the drawings, when by the downstrokes of the piston in working the pump the plunger is 15 operated, and thereby the valve of the tire positively operated, so that the valve is opened under the action of the compressed air and the so-called "sticking" of the valve overcome and an easier pumping action obtained, as the extra force required for opening 20 the valve under the pressure of the air is dispensed with, and by the positive action of the connection a quicker and more effective charging of the tire obtained.

25 Having thus described my invention, I claim as new and desire to secure by Letters Patent—

1. A pump connection for pneumatic tires, consisting of a cylindrical socket connected 30 with the pump, a cap screwed into the end of said socket, having a screw-threaded nipple, and a spring-actuated plunger in the socket, the stem of the plunger being guided in the bore of the screw-cap and nipple, sub- 35 stantially as set forth.

2. A pump connection for pneumatic tires, consisting of a socket provided with a nipple, said socket being formed of an upper cylin-

drical, an intermediate tapering and a lower threaded portion, a screw-cap provided with a 40 nipple screwed into the end of said socket, and a spring-actuated plunger in said socket, the stem of said plunger being guided in the bore of the screw-cap and nipple, substantially as set forth. 45

3. The combination of a pump connection consisting of a socket provided with a nipple at its closed end, a screw-cap at its lower end provided with a nipple, and a spring-cushioned plunger the stem of which extends into 50 said nipple, with a spring-cushioned valve on the tire provided with an exteriorly-threaded nipple for connection with the nipple on the screw-cap, for producing the positive opening of the valve by the stem of the plunger under 55 the action of the compressed air delivered into the socket, substantially as set forth.

4. The combination of a pump connection consisting of a cylindrical socket provided with a nipple, a screw-cap screwed into the 60 end of the socket and provided with an exteriorly-threaded nipple, and a spring-actuated plunger located in said socket and provided with a stem extending into the nipple of the screw-cap, with a valve in the tire provided with an interiorly-threaded nipple for the nipple of the screw-cap so as to bring the stem of the plunger in line with the stem of the valve of the tire, substantially as set forth. 65

In testimony that I claim the foregoing as 70 my invention I have signed my name in presence of two subscribing witnesses.

LEO RUMBOSKI.
